COLLAR CLASP

Reginald P. Borst, Washington, D. C.

Application March 7, 1950, Serial No. 148,092

2 Claims. (Cl. 24—81)

1

The present invention relates to improvements in collar clasps, and more particularly to a collar clasp having manually operable means for separating the clasping jaws to facilitate correct positioning of the clasp on the collar.

One object is to provide a collar clasp having a flexible bar member capable of being manipulated with one hand to separate the clamping jaw portions of the clasp and permit the jaws to clampingly engage the collar wings when released.

Another object is to provide a collar clasp in which the rear bar member is formed of yielding spring material having a finger engaging portion arranged such that when pressure is manually applied to said finger engaging portion the clamping jaws of said collar clasp will separate for insertion of the collar wings.

Another object is to provide a collar clasp in which the rear bar member is supported at spaced apart locations to provide a pair of fulcrum points about which the end portions of the bar rock when pressure is manually applied to the central portion of said bar, resulting in the flexing of the end portions or clamping jaw members of said bar member in a direction away from the front bar member.

Another object is to provide a collar clasp in which the front bar member is provided with a pair of spaced apart studs for supporting the rear or flexible clamping bar member and to provide pin and slot connections between said front and rear bar members to permit flexing of said rear bar member without binding.

Another object is to provide a collar clasp which can be conveniently and quickly applied with one hand, thus leaving the remaining hand free to hold the collar and tie in its correct position.

Another object is to provide a collar clasp which can be easily and economically manufactured and which is constructed of comparatively few parts to become out of adjustment.

Other objects and advantages of the invention will become apparent during the course of the following description of the accompanying drawings wherein:

Figure 1 is a front elevational view of a preferred embodiment of the invention.

Figure 2 is a rear elevational view showing one of the heads of the supporting studs broken away to illustrate the pin and slot connection.

Figure 3 is a longitudinal cross-sectional view taken on line 3—3 of Figure 1 looking in the direction of the arrows and illustrating various structural details.

2

Figure 4 is a top elevational view of the rear clamping bar of the collar clasp showing the same detached or removed from the front clasp bar.

Figure 5 is a transverse cross-sectional view taken on line 5—5 of Figure 3 looking in the direction of the arrows and showing the pin and slot connection between the front and rear clasp bars.

Figure 6 is a transverse cross-sectional view taken on line 6—6 of Figure 3 looking in the direction of the arrows and showing the manner in which the end portions of the flexible clamping bar are provided with projections or protuberances to frictionally engage the surface of the collar fabric.

Figure 7 is a rear elevational view of a modified form of the invention showing the flexible clamping rear bar slidably mounted and supported on a pair of spaced apart lugs on the front clasp bar and

Figure 8 is a side elevational view of the modified form of the invention shown in Figure 7 having a portion in section to illustrate the manner in which the rear clamping bar is attached to the front clasp bar.

In the drawing, and more in detail, attention is directed to Figures 1 to 6 inclusive wherein for the purpose of convenience of illustration there is shown a collar clasp generally designated 5 having a slightly bowed front bar 6 formed of metal having a suitable design on the front surface thereof.

Mounted on and intermediate the ends of the front bar 6 of the collar clasp is a pair of spaced studs 7 which are anchored in openings 8 by upsetting one of the ends of each as at 9 to form head portions countersunk in counterbored portions of the openings 8. Each of the studs 7 is provided with an annular enlarged portion 10 which seats against the rear surface of the front clasp bar 6 and cooperates with the upset head portions 9 to securely anchor said studs in position (Fig. 3).

The free ends of the studs are reduced in diameter to provide relatively short pin portions 11 and said pin portions are provided with enlarged heads 12 which can be formed by upsetting the ends with a suitable upsetting tool.

A rear clamping bar 14 is supported by the studs 7 and said clamping bar is provided with an intermediate finger engaging portion 15 and collar engaging portions 16 which are connected to the intermediate finger engaging portion 15 by slightly offset portions 17. The rear clamping bar is formed of yielding spring metal to cause

the collar engaging portions 16 to normally be yieldingly urged in a direction toward the ends of the front bowed collar clasp bar 6. The pin portions 11 are adapted to be received in elongated slots 19 formed in the rear clamping bar 14 to provide a pair of spaced apart pin and slot connections between the front collar clasp bar 6 and the rear or flexible collar clamping bar 14 (Fig. 5). It is to be noted, the slots 19 are spaced such that the adjacent ends engage the pin portions 11 of the studs so that endwise play of said rear clamping bar will be prevented, but yet permit the intermediate finger engaging portion 15 to be manually flexed to separate the collar engaging ends 16, or move the same in the direction of the arrows (Figs. 3) away from the corresponding ends of front bar member 6.

The free ends 16 of the flexible clamping bar 14 are bent slightly as at 20 in a direction away from the front bar 6 to facilitate easy entrance of the collar tabs, and a series of protuberances 22 are formed adjacent said ends to frictionally engage the fabric of the collar to which the clasp is applied.

In operation, the front of the bowed bar 6 and the finger engaging portion 15 of the rear or flexible bar 14 are grasped between the thumb and index finger such that pressure can be applied to the finger engaging portion 15 to move the same in a direction toward the front bar 6. As pressure is thus applied, the free end portions 16 of the rear flexible clamping bar 14 will separate from the corresponding ends of the front or bowed bar 6 a sufficient distance to permit the separated jaw portions to be slipped over the collar tabs or wings of a collar with each clamping jaw 16 engaging one of said collar wings or tabs. After the collar clasp has been properly placed in position beneath the tie, the pressure of the finger engaging portion 15 can be released so that the free ends 16 of the clamping bar 14 will frictionally and tightly grip the collar tabs or wings.

In the modified form of the invention shown in Figures 7 and 8, the front bar 6a of the collar clasp is slightly bowed and formed of semi-rigid metal and if desired, the front surface can be provided with a design to enhance the appearance of the collar clasp. The free end portions of the bar 6a provide stationary jaw members in substantially the same manner as the end portions of the front bar 6 shown and described in Figures 1 to 6 inclusive. Secured to the rear surface of the front bar 6a is a pair of spaced apart lugs or projections 7a which are positioned to extend in a slightly converging direction and said projections are provided with aligned slots 9a for slidably receiving a rear flexible clamping bar 14a. The intermediate portion of the flexible clamping bar 14a is provided with a relatively straight finger engaging portion 15a and the free ends are slightly curved in a direction toward the front collar clasp bar 6a as at 17a to form clamping jaw portions 16a.

Formed on the yielding clamping bar 14a adjacent each of the projections 7a is a protuberance 19a which is normally in contact with its corresponding projection 7a to prevent endwise

sliding movement of the yielding clamping bar 14a. Thus, the yielding clamping bar 14a is retained against displacement but is free to be flexed when pressure is exerted on the finger engaging portion 15a to separate the collar engaging jaw portions 16a as before.

It is to be noted, that the rounded surfaces of the protuberances 19a engage the projections 7a so that when pressure is applied to the finger engaging portion 15a the bar 14a will flex about these two points and the protuberances 19a will move away from said projections a slight distance.

It is to be understood, that the forms of the invention herewith shown and described are to be taken as preferred embodiments thereof, and that various changes in the shape, size and arrangement of parts can be resorted to without departing from the spirit of the invention or the scope of the subjoined claims.

I claim:

1. A collar clasp, comprising a pair of elongated bar members arranged in parallel spaced apart relation, one of said bar members being formed of yielding spring material and having its end portions bent to cooperate with the ends of the other bar member and form gripping jaws at each end of the collar clasp to frictionally grip the wings of a shirt collar, said bar member being provided with spaced elongated slots and spaced apart headed pin members carried by the intermediate rear portion of said other bar member adapted to be received in said slots to provide a pin and slot connection between said bar members, whereby pressure exerted on said yielding bar member between said connecting means will urge the end portions thereof away from said other bar member.

2. A collar clasp, comprising a pair of elongated bar members arranged in parallel spaced apart relation, one of said bar members being formed of yielding spring material and having its ends bent toward the other bar member to cooperate therewith and form yielding friction gripping jaws and a pair of studs secured to the intermediate portion of said other bar member in spaced apart relation, said studs provided with pin portions having heads on the ends thereof, and said yielding spring bar being provided with spaced apart slots for receiving said pin portions and providing pin and slot connections between said bar members, whereby pressure exerted on the intermediate portion of said yielding spring bar member will urge the free end portions outwardly away from said other bar member.
